GEORGE FRINK SPENCER, OF NEWARK, NEW JERSEY.

REFLECTOR.

No. 927,011.

Specification of Letters Patent.

Patented July 6, 1909.

Application filed May 14, 1908. Serial No. 432,813.

To all whom it may concern:

Be it known that we, WILLIAM H. SPENCER and JOHN A. CARLSTEDT, citizens of the United States, residing at Brooklyn, in the county of Kings and State of New York, have invented certain new and useful Improvements in Reflectors; and we do hereby declare the following to be a full, clear, and exact description of the invention, such as 10 will enable others skilled in the art to which it appertains to make and use the same, reference being had to the accompanying drawings, and to characters of reference marked thereon, which form a part of this specification. 15

Our present invention relates, generally, to improvements in reflectors; and, the invention has reference, more particularly, to improvements in that class of reflectors 20 which are provided with a hood or holder for the reception of an electric or other lamp-receiving socket and provided with means for the suspension or connection of the reflector to a stem, bracket, or other suitable means 25 of support.

The present invention has for its principal object to provide a simple and novel means for retaining the sectional reflecting elements or glasses within the reflector-casing 30 or shell; and, furthermore, to provide a novel construction of hood or holder for the reception of the lamp-socket, as well as a novel means and method of applying the holder which supports the reflector or shade to the 35 latter, with a view of providing a simple means of support and connection between the reflector-body or shade and a fitting by means of which the device is attached to a supporting stem, bracket, or the like, said 40 parts being arranged in such a manner, so that the supporting strain, which in the brackets as now ordinarily made is brought directly upon the lamp-socket, is entirely removed from the said lamp-socket.

Another principal object of our present invention is to provide simplicity of construction and ease in the manner of assembling the parts and arranging the hood or holder over a central opening in the reflector-body or shade, and furthermore to provide a 45 hood or holder which is formed with openings through which the fingers can be in-

serted for holding the lamp-socket in place while the parts are being assembled; and, also, to provide a hood or holder which has a 55 spring-like action, so as to be easily sprung into holding relation with the reflector-body or shade and is readily detachable from the said reflector-body or shade for convenience in packing the parts of the reflector for shipping. 60

Other objects of this invention not at this time more particularly enumerated will be clearly evident from the following detailed description. 65

With the various objects of our present invention in view, the said invention consists, primarily, in the novel reflector herein-after set forth; and, the invention consists, furthermore, in the various arrangements 70 and combinations of the devices and parts, as well as in the details of the construction of the same, all of which will be fully described in the following specification, and then finally embodied in the clauses of the 75 claims which are appended to and which form an essential part of this specification.

The invention consists, also, more particularly in the specific means of securing the reflecting-elements or glasses within the reflector-body or shell, the novel means and method of applying the hood or holder which supports the reflector-body or shade from the usual supporting stem, bracket, or the like, instead of on the shell of the lamp-socket; and also in the novel construction 80 of oscillating fitting for adjustably connecting or suspending the reflector from the suspension rod, bracket, or the like. 85

The invention is clearly illustrated in the 90 accompanying drawings, in which:—

Figure 1 is a view of the complete reflector embodying the principles of the present invention, the reflector being represented partly in elevation and partly in vertical 95 section. Fig. 2 is an elevation of the hood or holder, an adjustable fitting, and the upper portion of the reflector-body or shade, said parts being shown looking in a plane at right angles to the plane of view represented 100 in said Fig. 1. Fig. 3 is a top or plan view of the upper open portion of the reflector-body, shade, or shell, the hood or holder which supports said body or shell being

omitted from said view. Fig. 4 is a transverse vertical section taken on line 4—4 in said Fig. 2; and Fig. 4^a is a detail cross-section of the joint between the connected reflector-members. Fig. 5 is a diagrammatic view of a blank from which the main body or portion of said hood or holder is made; Fig. 6 is an elevation of said main body or portion of the hood or holder rolled or forced into its shape from the blank shown in said Fig. 5; and Fig. 7 is a top-end view of the main body or portion of the hood or holder shown in said Fig. 6, said Figs. 5, 6 and 7 being made on enlarged scales. Fig. 8 is a transverse vertical sectional representation of the upper portion of the reflector-body, shade, or shell, and a sectional representation of a hood or holder, showing a modified construction of securing the hood or holder in its fastened position over the upper open portion of the reflector-body, shade or shell. Similar characters of reference are employed in all of the above described views to indicate corresponding parts.

Referring now to the said figures of the drawings, the reference-character 1 indicates the complete reflector made according to and embodying the principles of our present invention. The reflector-body or shade in the present instance comprises an upper shade-member or shell 2 and a lower shade-member or shell 3, said upper shell being made with an inwardly bent marginal bead, as 4, and the lower shell being made with an outwardly bent marginal bead, as 5, over which the said bead 4 is fitted and firmly clamped down upon the same, so that the two shade-members or shells 2 and 3 are securely united, as will be clearly evident. The said bead 5 of the lower shell 3 is made with suitably formed and suitably disposed holding lugs or ears 6, which are bent downwardly and over the edge-portions of suitably formed reflector-elements or glasses 7 which are fitted upon the inner surface of the lower shade-member or shell 3, said elements or glasses 7 being suitably held in place by said lugs and a bead-like clamping ring 8 which is fitted upon and clamped directly over the lower marginal edge of the shade-member or shell 3 and the lower edge-portions of the reflector-elements or glasses 7, as clearly shown in Fig. 1 of the drawings. The said bead 5 of the lower shell 3 is also made with suitably formed and suitably disposed holding lugs or ears 9, which are bent upwardly and over the lower edge-portions of suitably formed reflector-elements or glasses 10 which are fitted upon the inner surface of the upper shade-member or shell 2, said elements or glasses being suitably held in place by said lugs or ears 9, and by a retaining ring 11 and a clamping or holding ring 12 suitably disposed in the upper central opening of the said upper shade-

member or shell 2, substantially in the manner to be presently described. One manner of connecting these parts is clearly illustrated in Fig. 4 of the drawings, the retaining ring 11 comprising a downwardly and inwardly bent marginal bead 13 which is fitted over and firmly clamped upon an outwardly projecting annular marginal edge-portion 14 of said shell 2. The said retaining ring 11 is made with an inwardly and downwardly extending part 15, which terminates in an upwardly extending annular marginal edge-portion or ring-shaped member 16, the upper edge-portions of the reflector-elements or glasses 10 abutting slightly against the inwardly and downwardly extending part 15 of the ring 11, substantially as shown.

The holding or clamping ring 12 is preferably of an arc-shaped cross-section, its marginal annular edge-portion 17 projecting beneath the lower and under part of the upwardly extending marginal edge-portion or ring-shaped member 16 of the ring 11, and said edge-portion 17 fitting directly upon the faces of the reflector elements or glasses 10, so as to securely hold the upper end-portions of said reflector-elements or glasses in place, as will be clearly understood. The said holding or clamping ring 12, after it has been inserted in its retaining relation with the upper shade-member or shell 2 and the ring 11 fitted thereto, in the manner just described, is detachably secured in said holding or clamping relation, by means of a series of holding or clamping tongues or prongs 18 which extend from the upper marginal edge of the ring 12 and are bent outwardly and directly upon the upper edge of the upwardly extending annular marginal edge-portion or ring-shaped member 16 of the ring 11, so that the various parts are securely and rigidly clamped in their assembled positions, with the upper end-portions of the reflector-elements or glasses 10 positively held in place. Any one or more of said elements or glasses 10 can be readily removed by bending back the holding or clamping tongues or prongs 18, so that the ring 12 can be removed from within the upper central opening of the upper shade-member or shell 2.

The hood or holder for attaching the reflector to a stem, bracket, or other suitable support, is indicated by the reference character 19, the holder shown in Figs. 1 to 7 inclusive, being blanked out of a piece of sheet-metal 20, (see Fig. 5), the same being formed with a series of projections or extensions 21, which are made with the variously shaped arc-shaped marginal edge-portions 22, 23, 24, 25 and 26, and which, when the blank 20 is rolled or pressed into the shape to form the hood or holder 19, are brought into an overlapped relation, as shown in the several figures of the drawings, so as to provide a hollow holder, formed with a lower and open cylind-

drical portion 27, and an upper ovoid portion, as 28, formed in its end with an opening 29, and in its sides with a series of other openings 30. As shown, the said hood or holder 5 which is thus provided, is also made in its cylindrical portion 27, with an outwardly projecting annular bead or groove 31. The purpose of this bead or groove 31 is to force the lower split and spring-like cylindrical 10 portion 27 directly over marginal bead 13 of the retaining ring 11, said bead or groove 31 being readily sprung or forced into its holding engagement with the bead 13, so as to positively but detachably connect the said hood 15 or holder 19 with the upper shade-member or shell 2 of the reflector, as will be clearly understood. Resting directly upon the upper end-portion of said hood or holder 19 is a dished or cup-shaped cap or disk-like plate 20 32 which is ornamental and also serves to hold the overlapping portions of the hood or holder together, the said plate 32 being formed with a centrally disposed hole or opening 33 which registers with the hole or 25 opening 29 in the upper end of the ovoid portion of said hood or holder 19, as clearly indicated in Fig. 4 of the drawings.

The reference-character 34 indicates any suitably formed lamp-socket which is provided upon its upper portion with a tubular member or nipple 35 formed with an externally screw-threaded part, substantially as shown. This lamp-socket 34 is arranged within the previously mentioned hood or 30 holder 19, with its upper and rounded end-portion bearing directly against the inner surface-portions of the overlapping parts of the ovoid portion of the hood or holder 19, with the screw-threaded nipple 35 extending 35 into and through the previously mentioned and registering holes or openings 29 and 33, as clearly shown in Fig. 4 of the drawings, a supporting fixture 37 which is provided with a screw-threaded hole or opening 38 being 40 screwed down upon said nipple, substantially as shown, for properly and rigidly securing the said devices in their assembled relation. The said fixture 37 may also be provided with upwardly extending ears or 45 lugs 39 which are provided with screw-receiving holes. Another fixture 40 may also be provided, said fixture 40 being formed with downwardly extending ears or lugs 41 which are also made with screw-threaded holes, 50 adapted to be brought in juxtaposition to the screw-holes in the ears or lugs 39 of the fixture 37, so as to register with the same, and so that the ears or lugs of the respective fixtures 37 and 40 can be adjustably connected by means of the short connecting screws 42, which act both as adjusting and tightening screws, as will be clearly understood. In its main body-portion, the fixture 60 40 is made with an internally screw-threaded hole 43 for arranging the said fixture upon

the screw-threaded end-portion 44 of a tubular rod, bracket, or other suitable supporting means, from which the reflector is to be suspended. It will thus be seen, that we have provided a neat and simply constructed device for applying the reflector or shade by means of the hood or holder, in which the lamp-socket is arranged, directly to the end of a stem, bracket, or the like, instead of applying the reflector or shade directly to the thin shell of the lamp-receiving socket, whereby a strong and durable arrangement of the various parts is clearly the result. 70 75

By slightly loosening the pivot-screws 42, the two fixtures 37 and 40 can be set at different angles, so as to provide for the adjustment of the reflector-shade, the screws being tightened up again after the adjustment of the reflector-shade has been made. 80

A further advantage obtained by the use of the hood or holder 19 hereinabove described, and provided with suitably disposed openings, as 30, is that thereby a means is furnished for the insertion of the fingers through said openings into the interior of the 85 hood or holder, so as to hold the lamp-receiving socket in place while assembling the various parts in their rigidly connected relations. 90

In Fig. 8 of the drawings, we have shown slightly modified means for attaching the 95 hood or holder to the reflector-body or shade, and for at the same time securing the upper end-portions of the reflector-elements or glasses 10 to the inner surface of the upper shade-member or shell 2. In this construction, the retaining ring 11 is secured in the upper open portion of the shell 2 in the same manner as described in connection with the construction shown in said Fig. 4, but the clamping or holding ring 12 is dispensed 100 with, and the lower cylindrical portion 27 of the hood or holder 19 is made of a reduced cross-section, so that the annular bead 31 will rest upon the upwardly extending annular marginal edge-portion or ring-shaped member 16 of the ring 11, as clearly illustrated in said Fig. 8. Extending from the lower marginal edge of the cylindrical body-portion 27 of said hood or holder 19 is an arrangement of holding lugs or tongues 105 110 which are suitably bent against the upper edge-portions of the reflector-elements or glasses 10, whereby the latter are suitably secured in place, in the manner clearly shown in said Fig. 8. 115

We are fully aware that some changes may be made in the various arrangements and combinations of the devices and parts, as well as in the details of the construction of the same, without departing from the scope 125 of the present invention as described in the foregoing specification and as defined in the claims which are appended to said specification. Hence we do not limit our invention to the exact arrangements and combina- 130

tions of the devices and parts as described in the foregoing specification, nor do we limit ourselves to the exact details of the construction of the parts as illustrated in the accompanying drawings.

We claim:-

1. A reflector comprising a reflector-body or shade consisting of an upper and a lower shell, said upper shell being provided with a centrally disposed opening for the arrangement of a lamp-receiving socket therein, said upper shell being provided with an inwardly bent marginal bead, and said lower shell being provided with an outwardly projecting marginal bead extending into the marginal bead of said upper shell, the marginal bead of said upper shell embracing the marginal bead of the lower shell and being tightly clamped down upon the same, clamping tongues extending from the marginal bead of said lower shell, reflector-elements or glasses arranged upon the inner surfaces of said upper and lower shells with which said tongues are in retaining engagement, and retaining means respectively at the upper and lower end-portions of the lower and upper shells in holding engagement with other portions of said reflector-elements, substantially as and for the purposes set forth.
2. A reflector comprising a reflector-body or shade consisting of an upper and a lower shell, said upper shell being provided with a centrally disposed opening for the arrangement of a lamp-receiving socket therein, said upper shell being provided with an inwardly bent marginal bead, and said lower shell being provided with an outwardly projecting marginal bead extending into the marginal bead of said upper shell, the marginal bead of said upper shell embracing the marginal bead of the lower shell and being tightly clamped down upon the same, clamping tongues extending from the marginal bead of said lower shell, reflector-elements or glasses arranged upon the inner surfaces of said upper and lower shells with which said tongues are in retaining engagement, a clamping ring arranged in the centrally disposed opening of said upper shell, clamping tongues extending from said ring in holding engagement with said upper shell, and means upon the lower end-portion of said lower shell in holding engagement with the lower end-portions of said reflector-elements or glasses in said lower shell, substantially as and for the purposes set forth.
3. A reflector comprising a reflector-body or shade consisting of an upper and a lower shell, said upper shell being provided with a centrally disposed opening for the arrangement of a lamp-receiving socket therein, said upper shell being provided with an inwardly bent marginal bead, and said lower shell being provided with an outwardly projecting marginal bead extending into the marginal

bead of said upper shell, the marginal bead of said upper shell embracing the marginal bead of the lower shell and being tightly clamped down upon the same, clamping tongues extending from the marginal bead of said lower shell, reflector-elements or glasses arranged upon the inner surfaces of said upper and lower shells with which said tongues are in retaining engagement, a clamping ring arranged in the centrally disposed opening of said upper shell, clamping tongues extending from said ring in holding engagement with said upper shell, and a bead-like clamping ring in clamped engagement with the lower marginal edge of said lower shell and the lower end-portions of the reflector-elements or glasses in said lower shell, substantially as and for the purposes set forth.

4. A reflector comprising a reflector-body or shade provided with a centrally disposed opening, reflector-elements or glasses arranged upon the inner surface of said reflector body, a retaining ring secured within said centrally disposed opening to said reflector body, said ring being provided with an upwardly extending annular marginal ring-shaped member, a clamping-ring arranged within said retaining ring, and clamping tongues extending from said clamping ring, said tongue being bent over and being in supporting engagement with the ring-shaped member of said retaining ring, substantially as and for the purposes set forth.

5. A reflector comprising a reflector-body or shade provided with a centrally disposed opening, said opening being bounded by an outwardly extending marginal edge-portion, reflector-elements or glasses arranged upon the inner surface of said reflector-body, a retaining ring secured within said centrally disposed opening to said reflector-body, said retaining ring being provided with a downwardly and inwardly bent marginal bead clamped about the outwardly extending marginal edge-portion of said reflector-body, said retaining ring being provided also with an upwardly extending annular marginal ring-shaped member, a clamping-ring arranged within said retaining ring, and clamping tongues extending from said clamping ring, said tongue being bent over and being in supporting engagement with the ring-shaped member of said retaining ring, substantially as and for the purposes set forth.

6. A reflector comprising a reflector-body or shade provided with a centrally disposed opening, said opening being bounded by an outwardly extending marginal edge-portion, reflector-elements or glasses arranged upon the inner surface of said reflector-body, a retaining ring secured within said centrally disposed opening to said reflector-body, said retaining ring being provided with a downwardly and inwardly bent marginal bead

- clamped about the outwardly extending marginal edge-portion of said reflector-body, said retaining ring being provided also with an upwardly extending annular marginal ring-shaped member, a clamping-ring arranged within said retaining ring, and clamping tongues extending from said clamping ring, said tongues being bent over and being in supporting engagement with the ring-shaped member of said retaining ring, said clamping ring having a portion in retaining engagement with said reflector-elements and clamping means connected with other portions of said reflector-body in holding engagement 10 with said reflector-elements or glasses, substantially as and for the purposes set forth. 70

7. A reflector comprising a reflector-body or shade provided with a centrally disposed opening for the arrangement of a lamp-receiving socket therein, and a slitted hood formed with retaining portions, each retaining portion having a spring-like action, and means connected with each retaining portion for detachably connecting said hood to 20 the reflector-body, said hood being provided in its upper portion with an opening through which a portion of the lamp-receiving socket extends, substantially as and for the purposes set forth. 80

8. A reflector comprising a reflector-body or shade provided with a centrally disposed opening for the arrangement of a lamp-receiving socket therein, said opening being bounded by a bead-like portion, and a slitted 25 hood formed with retaining portions, each retaining portion having a spring-like action and being provided with an annular groove adapted to be sprung over said bead-like portion, substantially as and for the purposes set forth. 90

9. A reflector comprising a reflector-body or shade provided with a centrally disposed opening for the arrangement of a lamp-receiving socket therein, said opening being bounded by a bead-like portion, and a slitted 30 hood formed with retaining portions, each retaining portion having a spring-like action and being provided with an annular groove adapted to be sprung over said bead-like portion, substantially as and for the purposes set forth. 100

10. A reflector comprising a reflector-body or shade provided with a centrally disposed opening for the arrangement of a lamp-receiving socket therein, reflector-elements or glasses arranged upon the inner surface of 35 said reflector-body, a retaining ring within said centrally disposed opening, said ring being provided with an upwardly extending annular marginal ring-shaped member, a clamping ring within said retaining ring, said clamping ring having a portion in retaining engagement with said reflector-elements, clamping tongues extending from said clamping ring over and in engagement with the ring-shaped member of said retaining ring, said retaining ring being provided with an outer marginal bead, and a slitted hood 40 formed with retaining portions, each retaining portion having a spring-like action and being provided with an annular groove adapted to be sprung over the bead of said retaining ring, substantially as and for the purposes set forth. 110

11. A reflector comprising a reflector-body or shade provided with a centrally disposed opening for the arrangement of a lamp-receiving socket therein, reflector-elements or glasses arranged upon the inner surface of 45 said reflector-plate, means for retaining said reflector-elements or glasses upon the inner surface of said reflector-plate, a retaining ring within said centrally disposed opening, said ring being provided with a marginal bead, and a slitted hood formed with retaining portions, each retaining portion having a spring-like action and being provided with an annular groove adapted to be sprung over the bead of said retaining ring, substantially as and for the purposes set forth. 120

12. A reflector comprising a reflector-body or shade provided with a centrally disposed opening for the arrangement of a lamp-receiving socket therein, reflector-elements or glasses arranged upon the inner surface of 50 said reflector-body, a retaining ring within said centrally disposed opening, said ring being provided with an upwardly extending annular marginal ring-shaped member, a clamping ring within said retaining ring, said clamping ring having a portion in retaining engagement with said reflector-elements, clamping tongues extending from said clamping ring over and in engagement with the ring-shaped member of said retaining ring, said retaining ring being provided with an outer marginal bead, and a slitted hood 55 formed with retaining portions, each retaining portion having a spring-like action and being provided with an annular groove adapted to be sprung over the bead of said retaining ring, substantially as and for the purposes set forth. 130

13. A reflector comprising a reflector-body or shade provided with a centrally disposed opening for the arrangement of a lamp-receiving socket therein, reflector-elements or glasses arranged upon the inner surface of 60 said reflector-body, a retaining ring within said centrally disposed opening, said ring being provided with a marginal bead, and a slitted hood formed with retaining portions, each retaining portion having a spring-like action and being provided with an annular groove adapted to be sprung over the bead of said retaining ring, substantially as and for the purposes set forth. 140

being provided with an annular groove adapted to be sprung over the bead of said retaining rim, said hood being provided in its sides with openings, and in its upper portion with an opening through which a portion of the lamp-receiving socket extends, substantially as and for the purposes set forth.

14. A reflector comprising a reflector-body or shade provided with a centrally disposed opening for the arrangement of a lamp-receiving socket therein, said opening being bounded by an outwardly extending marginal edge-portion, reflector-elements or glasses arranged upon the inner surface of said reflector-body, a retaining ring within said centrally disposed opening, said retaining ring being provided with a downwardly and inwardly bent marginal bead clamped about the outwardly extending marginal edge-portion of said reflector-body, said retaining ring being provided also with an upwardly extending annular marginal ring-shaped member, a clamping-ring arranged within said retaining ring, said clamping ring having a portion in retaining engagement with said reflector-elements, and clamping tongues extending from said clamping-ring over and in engagement with the ring-shaped member of said retaining ring, and a slotted hood formed with retaining portions each retaining portion having a spring-like action and being provided with an annular groove adapted to be sprung over the bead of said retaining ring, substantially as and for the purposes set forth.

15. A reflector comprising a reflector-body or shade provided with a centrally disposed opening for the arrangement of a lamp-receiving socket therein, said opening being bounded by an outwardly extending marginal edge-portion, reflector elements or glasses arranged upon the inner surface of said reflector-body, a retaining ring within said centrally disposed opening, said retaining ring being provided with a downwardly and inwardly bent marginal bead clamped about the outwardly extending marginal edge-portion of said reflector-body, said retaining ring being provided also with an upwardly extending annular marginal ring-shaped member, a clamping-ring arranged within said retaining ring, said clamping ring having a portion in retaining engagement with said reflector-elements, and clamping tongues extending from said clamping ring over and in engagement with the ring-shaped member of said retaining ring, and a slotted hood formed with retaining portions, each retaining portion having a spring-like action and being provided with an annular groove adapted to be sprung over the bead of said retaining ring, said hood being provided in its sides with openings, and in its upper portion with an opening through which a portion of

the lamp-receiving socket extends, substantially as and for the purposes set forth.

16. A reflector comprising a reflector-body provided with a centrally disposed opening, a hood connected with said reflector-body, said hood being provided in its upper portion with an opening, a lamp-receiving socket within said hood, a screw-threaded nipple extending from said socket through the opening in said hood, a fixture provided with a screw-threaded hole screwed upon said nipple, said fixture being provided with ears, each ear being formed with a screw-hole, a second fixture provided with a screw-threaded hole for attachment of said fixture to a stem, or the like, said fixture being provided with ears, and each ear being formed with a screw-hole, and pivotal screws connecting the ears of the respective fixtures, substantially as and for the purposes set forth.

17. A reflector comprising a reflector-body provided with a centrally disposed opening, said opening being bounded by a bead-like portion, a slotted hood formed with spring-like retaining portions and an annular groove adapted to be sprung over said bead-like portion, said hood being provided in its upper portion with an opening, a lamp-receiving socket within said hood, a screw-threaded nipple extending from said socket through the opening in said hood, a fixture provided with a screw-threaded hole screwed upon said nipple, said fixture being provided with ears, each ear being formed with a screw-hole, a second fixture provided with a screw-threaded hole for attachment of said fixture to a stem, or the like, said fixture being provided with ears, and each ear being formed with a screw-hole, and pivotal screws connecting the ears of the respective fixtures, substantially as and for the purposes set forth.

18. A reflector comprising a reflector-body or shade provided with a centrally disposed opening, a retaining ring within said centrally disposed opening, said ring being provided with a marginal bead, a slotted hood formed with spring-like retaining portions and an annular groove adapted to be sprung over the bead of said retaining ring, said hood being provided in its upper portion with an opening, a lamp-receiving socket within said hood, a screw-threaded nipple extending from said socket through the opening in said hood, a fixture provided with a screw-threaded hole screwed upon said nipple, said fixture being provided with ears, each ear being formed with a screw-hole, a second fixture provided with a screw-threaded hole for attachment of said fixture to a stem, or the like, said fixture being provided with ears, and each ear being formed with a screw-hole; and pivotal screws con-

necting the ears of the respective fixtures, substantially as and for the purposes set forth.

19. A reflector comprising a reflector-body or shade provided with a centrally disposed opening, said opening being bounded by an outwardly extending marginal edge-portion, reflector-elements or glasses arranged upon the inner surface of said reflector-body, a 10 retaining ring within said centrally disposed opening, said retaining ring being provided with a downwardly and inwardly bent marginal bead clamped about the outwardly extending marginal edge-portion of said 15 reflector-body, said retaining ring being provided also with an upwardly extending annular marginal ring-shaped member, a clamping-ring arranged within said retaining ring, said clamping ring having a portion in 20 retaining engagement with said reflector-elements, and clamping tongues extending from said clamping ring over and in engagement with the ring-shaped member of said retaining ring, a slotted hood formed with 25 retaining portions, each retaining portion having a spring-like action and being pro-

vided with an annular groove adapted to be sprung over the bead of said retaining ring, said hood being provided in its upper portion with an opening, a lamp-receiving socket 30 within said hood, a screw-threaded nipple extending from said socket through the opening in said hood, a fixture provided with a screw-threaded hole screwed upon said nipple, said fixture being provided with ears, 35 each ear being formed with a screw-hole, a second fixture provided with a screw-threaded hole for attachment of said fixture to a stem, or the like, said fixture being provided with ears, and each ear being formed 40 with a screw-hole, and pivotal screws connecting the ears of the respective fixtures, substantially as and for the purposes set forth.

In testimony, that we claim the invention 45 set forth above we have hereunto set our hands this 9th day of May, 1908.
